United States Patent Office

Des. 206,580
Patented Jan. 3, 1967

206,580

BUILDING

Henry W. Beckman, Spanish Lake, Mo.
(12330 Larimore, St. Louis, Mo. 63138)

Filed Dec. 8, 1965, Ser. No. 255

Term of patent 14 years

(Cl. D13—1)

FIG. 1

FIG. 2

FIG. 3

FIG. 4

FIG. 1 is a top plan view of the building showing my new design;

FIG. 2 is an elevational view (as seen from a plane represented by line 2-2 of FIG. 1);

FIG. 3 is an elevational view (as seen from a plane represented by line 3-3 of FIG. 1); and

FIG. 4 is an elevational view (as seen from a plane represented by line 4-4 of FIG. 1).

The dominant features of my design reside in the full line portions shown above the ground lines.

I claim:

The ornamental design for a building, substantially as shown and described.
